UNITED STATES PATENT OFFICE.

ISAAC HIRSCH, OF CHICAGO, ILLINOIS.

DESIGN FOR A HANDLE FOR KNIVES, FORKS, AND OTHER ARTICLES OF CUTLERY.

48,895.

Specification for Design.

Patented Apr. 18, 1916.

Application filed January 4, 1916. Serial No. 70,306. Term of patent 14 years.

To all whom it may concern:

Be it known that I, ISAAC HIRSCH, a citizen of the United States, residing at Chicago, in the county of Cook and State of Illinois, have invented a new, original, and ornamental Design for a Handle for Knives, Forks, and other Articles of Cutlery, of which the following is a specification, reference being had to the accompanying drawing, forming a part hereof.

Figure 1 is a face view, and Fig. 2, an edge view of a handle for knives, forks and

other articles of cutlery, in accordance with my new design.

I claim:

The ornamental design for a handle for knives, forks and other articles of cutlery, as shown.

ISAAC HIRSCH.
